ABSTRACT: A sealing disc for use with a corrugated type cap closure for a bottle is made of nonrigid synthetic resin and has a thin, filmlike flange on its periphery. Projections are formed on the disc near its periphery for closely contacting the edge of the bottle opening and the adjacent surface of the cap closure. Additional annular projections are formed in the central region of the disc for contacting the inner surface of the cap. Upon capping the bottle, the filmlike flange is pressed into the internal recesses formed in the corrugated side portions of the cap and assists in sealing the bottle.

SEALING DISC FOR CROWN CLOSURES

BACKGROUND OF THE INVENTION

It is well-known to use a sealing disc for bottle cap or crown closures, which are made of a synthetic resin. These discs are provided, in the main body thereof, with the following: an inner annular projection or rim adapted to press the inner peripheral wall of a bottle mouth and located on the upper and lower surfaces of the boundary between the peripheral portion of the bottle top and the central portion placed over the opening of the bottle mouth, an outer annular projection adapted to press the external peripheral wall of the bottle mouth on upper and lower surfaces of said periphery, annular grooves formed symmetrically on upper and lower surfaces, respectively, on a portion where the base portion of the outer annular projection and the peripheral portion contact, inclined surfaces sloping down outwardly formed on upper and lower surfaces of the outer annular projection, and the inside diameter of the main portion of up to the neck portion of the outer annular projection being made substantially equal to the inside diameter of the cap or crown closure, whereby the outer annular projection is made to contact against the inner peripheral wall of the crown closure by bending at the annular grooves.

With the above described sealing disc for crown closures, however, the degree of intrusion or flow of the outer annular projection into the internal recesses formed by the corrugations on the skirt portion of the crown closure is incomplete, and since the central portion of the disc is in contact with the inner surface of the top plate of the crown closure, there has been the disadvantage that the sealing effect was prevented because of the deformation due to the pressure within the bottle.

The sealing disc for a crown closure according to the present invention is excellent in its sealing effect due to a construction that includes a thin, filmlike flange or projection extending laterally from the periphery of the circular main body which is pressed into the recesses formed on the inside of the corrugated wall of the crown skirt so that no gap is formed therebetween, and concentric annular projections located in the central portion of the disc and arranged to contact the inner surface of the top plate of the crown closure for preventing the deformation of the sealing disc due to the pressure inside the bottle.

SUMMARY OF THE INVENTION

The object of the present invention is to provide a sealing disc for a crown closure which can be fitted firmly into the cap body without the fear of being detached, the crown cap, fitted with the disc according to the present invention, being mounted on the mouth of a bottle, the disc in the crown cap will not be deformed, during the use, by the pressure within the bottle, thus the sealing effect thereof is much improved.

According to the invention, in mounting the sealing disc in the metal crown cap, the thin, filmlike flange is made to contact the inside of the corrugated skirt portion of the crown body by bending at the base portion of the filmlike flange, and the main body of the disc, which is made of synthetic resin, according to the present invention is fitted closely inside the crown cap by its elasticity.

In accordance with the present invention, the main body of the disc for the crown cap is maintained flat because the top portions of the concentric projections press against the top plate of the crown and this, maintains the exact position of the disc inside the crown body.

Furthermore, in accordance with the present invention, the filmlike flange portion is pressed into the interior recesses in the corrugated wall formed on the skirt portion of the crown body, and this engagement maintains the main body of the disc firmly and immovably within the crown body.

When a crown closure fitted with the disc, according to the present invention, is capped on the mouth of a bottle, with the pressing contact of the upper side of the inner annular projection of the disc on the inner surface of the top plate of the

crown cap, the lower side of the inner annular projection is pressed against the inner shoulder of the bottle mouth, and at the same time the upper side of the outer annular projection or rim portion is pressed against the inner shoulder of the cap body, and the lower side of the rim is pressed against the outer shoulder of the bottle mouth, the lower side of the inner annular projection and the lower side of the rim portion are fitted closely on the edge portion of the bottle mouth, thus completely sealing the bottle.

10 With the disc for a crown closure according to the present invention, the top portions of the concentric annular projections in the central portion of the disc press against the inner surface of the top plate of the crown body and support the central portion securely inside the inner annular projection, so that any deformation of the central portion itself due to the pressure inside the bottle can be prevented, and no gap between the annular projection and the inner shoulder portion of the bottle mouth is produced, and thus extremely excellent sealing can be maintained.

15 According to the present invention, the mechanical strength at the central portion of the disc is increased by the provision of the concentric annular projections, and during the use of the crown closure fitted with the disc of the present invention on the bottle mouth, the disc of the crown cap shows a favorable resistance against the pressure produced inside the bottle, and no deformation such as extension will ever be produced.

20 With the disc of a crown closure according to the present invention, the radial tension of the central portion is essentially supported by the concentric annular projections, the tension being transmitted uniformly to the annular projection, the deformation of the annular projection can be checked favorably and the sealing effect is maintained positively.

25 Furthermore, a disc of the crown closure of the present invention gives a favorable result although a nonrigid synthetic resin material is used in molding the disc. That is, in the cooling and setting course during the molding of the disc, the thin portions of the disc cool down and set previous to the thick, projecting portions of the disc which are still in a molten state, and the deformation of said thin portions of the disc liable to be produced by their quick cooling is prevented by the thick portion where the heat capacity is greater, thus an appropriate plastic disc having no internal strain, and therefore no twisting or flexure is formed.

45 BRIEF DESCRIPTION OF THE DRAWING

FIG. 1 is a plan view of the disc for a crown closure according to the present invention;

50 FIG. 2 is a cross-sectional view along the line II-II of FIG. 1;

FIG. 3 is a cross-sectional view of the disc according to the present invention showing the state in which the disc is inserted in a crown closure; and

FIG. 4 is a cross-sectional view of the disc showing the

55 crown closure when the latter is capped on the mouth of a bottle.

DESCRIPTION OF THE PREFERRED EMBODIMENT

The invention will now be described with an embodiment referring to the appended drawings.

60 A circular disc made of a nonrigid synthetic resin comprises a rim portion 2, 2a and an annular projection 3, 3a each projecting from an opposite side of the main body 1, a thin, filmlike flange portion 5 extends laterally in a horizontal plane from; and circumferentially about the central portion of the vertical peripheral wall 4 of the main body 1. A pair of concentric annular projections 7, 7a, 8, 8a extend from each face of the central portion 6 of the disc located inwardly from the annular projection 3, 3a, and an annular groove 9, 9a is provided on each surface of the base portion of the rim 2, 2a adjacent the annular projection 3, 3a.

65 The annular rim portion 2, 2a, the annular projection 3, 3a, the concentric annular projections 7, 7a, 8, 8a and the annular groove 9, 9a are all formed symmetrically on the upper and lower surfaces of the main body 1.

The rim portion 2, 2a is formed corresponding to the outer shoulder portion 10a of the mouth 10 of the bottle, see FIG. 4, and the annular projection 3, 3a is formed corresponding to the inner shoulder portion 10b of the bottle mouth 10, and inclined faces 3, 3a, sloping towards the rim 2, 2a are formed from the top portions of the annular projection 3, 3a. The thin, filmlike flange 5 is made to contact the inner and upper portions of the corrugated wall formed on the skirt portion of the crown body 11, and is formed so as to be pressed into the recessed portions 11a inside the corrugated wall. The top portions of the concentric annular projections 7, 7a, 8, 8a and the annular projection 3, 3a are each made to have a height which when the disc is inserted in the crown cap, each of the top portions contacts the top plate 11b of the cap body 11 as shown in FIG. 3.

A preferable shape and dimensions for the disc for a crown closure according to the present invention are as follows: when the diameter 1 (see FIG. 2) of the outer peripheral wall 4 of the main body 1 is 27 mm., it is proper to for the thickness d_1 of the main body 1 to be 0.2 to 1 mm., the thickness d_2 of the flange 5 to be one-half to one-third of the thickness d_1 of the main body 1, the width w_1 of the flange 5 to be one-fiftieth to one-tenth of the diameter of outer peripheral wall portion 4 of the main body 1, the height h_1 from the flat surface of the central portion 6 of the main body 1 to the top portion of the annular projection 3, 3a to be 0.5 to 1 mm., the height h_2 from the flat surface at the central portion of the main body 1 to the top of the concentric projections 7, 7a, 8, 8a to be 0.2 to 1 mm., and the width w_2 of each of the concentric projections to be 0.4 to 2 mm., respectively.

The disc for a crown closure according to the present invention being thus constructed, in inserting the disc into the crown body 11, the filmlike flange 5 bends itself at the base portion thereof so as to be pressed into the recessed portions 11a of the corrugated wall formed on the skirt portion of the crown body 11, and the main body of the disc due to its elasticity is inserted into engagement with the crown body 11.

Since the top portions of the concentric projections 7, 8 or those of the concentric projections 7a, 8a (when the disc is used upside-down) are made to contact with the inner surface of the top plate 11b of the crown body 11, the main body 1 of the disc is maintained flat, and is inserted and engaged in the correct position.

When the crown closure fitted with the disc is capped on the mouth of a bottle, the filmlike flange portion 5 is pressed and made to contact the upper portion of the corrugated wall formed in the skirt portion of the crown body 11, and the parts thereof are pressed into the recesses 11a of the corrugated wall, so that the main body 1 of the disc is held firmly and immovably within the crown cap 11, and at the same time since the flange portion 5 is deformed within the recesses 11a, and no gap is allowed to form therebetween. When fitting the crown closure including the disc on the mouth 10 of a bottle, by the deformation of the annular projection 3 when it is pressed against the inner surface of the top plate 11b of the crown body 11, the annular projection 3a of the opposite side is pressed against the inner shoulder 10b of the bottle mouth 10, and at the same time, the rim portion 2 is pressed by the inner shoulder of the crown body 11, so that the rim portion 2a at the opposite side is pressed against the outer shoulder portion 10a of the bottle mouth 10, closing the bottle completely.

Since the top portions of the concentric projection 7, 8 contact with the inner surface of the top plate 11b of the crown body 11, and support the central portion 6 located inside the annular projection 3, 3a, the deformation of the central portion 6 itself due to the pressure inside the bottle can be prevented, and no gap is formed between the annular projection 3a and the inner shoulder portion of the bottle mouth 10, thus maintaining an extremely complete sealing effect.

The grooves 9, 9a assist the deformation of the rim portion 2, 2a and the annular projections 3, 3a to fit closely on the outer shoulder 10a and the inner shoulder 10b of the bottle

mouth 10.

The disc for a crown closure according to the present invention may be fitted closely inside the crown body without any fear of it falling out, and when the crown closure fitted with the disc is capped on the bottle mouth, no gap is formed between the edge of the bottle mouth and the crown body, a close and complete sealing effect is maintained, and together therewith, an extremely large resistance against pressure may also be formed.

10 In this embodiment, there is shown two concentric annular projections, but it is to be understood that, for example, one or three or more of the concentric projections may also be provided.

I claim:

- 15 1. A sealing disc adapted to be inserted into a crown closure for sealing the mouth of a bottle, the crown closure having a corrugated skirt portion arranged to extend downwardly about the periphery of the bottle at its mouth, the sealing disc being formed of a nonrigid synthetic resin and comprising a flat circular main body having a first surface and an oppositely facing second surface with the first and second surfaces being 20 symmetrically shaped, a rim portion extending continuously about the circumferential periphery of said main body and extending generally perpendicularly outwardly from the first and second surfaces of said main body, said rim having a radially outwardly directed circumferentially extending peripheral surface extending transversely of the plane of said main body, a filmlike flange extending radially outwardly from the peripheral surface of said rim in generally coplanar relationship with said main body, an outer annular projection extending generally perpendicularly outwardly from the first and second surfaces of said main body and being spaced inwardly from said rim portion thereon, the radially outer surfaces of 30 said outer annular projection located perpendicularly outward from each of the first and second surfaces of said main body sloping outwardly toward said rim portion and intersecting the first and second surfaces at an oblique angle to the plane of said main body and being arranged to form a surface adapted to conform to the top surface of the bottle encircling the opening to be sealed by the combination of the crown closure and said sealing disc, an annular groove being cut into each of the first and second surfaces of said body between said rim portion and said outer annular projection and at least one inner 40 annular projection extending generally perpendicularly outwardly from the first and second surfaces of said main body and being spaced inwardly from said outer annular projection, whereby when the disc is inserted into the crown closure said filmlike flange is pressed into the recessed portions formed by the corrugated skirt portion and forms a seal therewith for 45 securing the disc within the crown closure and said inner and outer projections extending from the first surface of said main body into contacting engagement with the inner surface of the crown closure which is arranged to span the mouth of the bottle and when the crown closure and said sealing disc are 50 pressed onto the mouth of the bottle said rim portion extending from the second surface of said main body being in sealing contact with the outer periphery of the bottle at its mouth and said outer annular projection extending outwardly from the second surface of said main body in sealing contact with the inner periphery of the bottle at its mouth.

60 2. A sealing disc, as set forth in claim 1, wherein said filmlike flange having a thickness about one-third to one-half the thickness of said main body.

3. A sealing disc, as set forth in claim 2, wherein said flange having a dimension in the radial direction of between one-fifth to one-tenth of the diameter of said main body portion.

65 4. A sealing disc, as set forth in claim 1, wherein the dimension of said inner and outer annular projections extending from the first and second surfaces of said main body being substantially the same and being greater than the dimension of said rim portion from said first and second surfaces of said main body.
